INVENTOR,
BY *Joseph J. Gage,*
Howard S. Smith.
His ATTORNEY

UNITED STATES PATENT OFFICE

JOSEPH J. GAGE, OF DAYTON, OHIO, ASSIGNOR TO LESTER W. COATE, OF DAYTON, OHIO
COMBINATION HOT-WATER HEATER AND STEAM GENERATOR

Application filed May 20, 1929. Serial No. 364,437.

This invention relates to new and useful improvements in combination hot water heaters and steam generators.

It is one of the principal objects of my invention to provide a combination hot water heater and steam generator which is so constructed as to permit a thorough and complete circulation of the water in contact with its heated surfaces so that only a minimum amount of heat is wasted. The water, admitted to the lower row of tubes, circulates completely through them before it enters the row above, this circulatory course through all the tubes of each row being enforced before the heated water or steam passes out of the last tube of the top row into the storage tank.

It is another object of my invention to provide a simple and compact combination hot water heater and steam generator having easily removable closure parts to permit convenient access to the tubes for the removal of sediment therefrom. If it is not possible to remove the scale, a boiler will soon burn out.

Other important and incidental objects will be brought out in the following specification and particularly set forth in the subjoined claims.

In the accompanying drawings illustrating my invention, Figure 1 is a vertical sectional view taken through my combination hot water heater and steam generator. Figure 2 is a top plan view of the header portion of the same. And Figure 3 is a side view, with the cover removed, of one side of the header, showing the disposition of the tubes and partitions for directing the circulatory course of the water to be heated or converted into steam.

Referring to the accompanying drawings for a detailed description of the form of embodiment of my invention disclosed therein, the numeral 1 designates a base which is preferably a hollow casting that flares outwardly at its bottom for a firm support upon a flat surface. A short distance below the top of the casting there extends from wall to wall a support 2 for a burner 3.

Formed at the top marginal edge of the casting 1 is an inwardly turned flange 4,

which supports, and to which there is bolted, an external flange 5 on the bottom of a header casting 6. Fitted in holes in the sides 7, 7 of the latter are rows, one above the other, of horizontal tubes 8.

Provided at the marginal edge of the top of the header casting 6 is a flange 9 similar to the flange 5. Against the flanges 5 and 9 on each side of the header casting 6, there is secured by studs 10 a side cover plate 11. These studs are received by tapped holes in ears 12 on the casting walls so that the cover plates 11 may be easily removed by a withdrawal of the studs to afford convenient access to the tubes 8 so that they may be easily and thoroughly cleaned with a steel brush.

Into the space between each cover plate 11 and its respective casting side 7 there project from the latter, vertical baffle partitions 13 and horizontal baffle partitions 14. As shown in the drawings, the vertical partitions 13 are alternately disposed between the ends of the tubes 8, so that when the water enters the header casting through an inlet 15 communicating with the space opposite the bottom row of tubes on one side, it will be compelled, by the vertical partition between the end of the first tube and the end of the second tube, to enter the former and pass through it to the space on the other side of the header casting opposite the bottom row of tubes. Here the next vertical partition 13, as indicated by the dotted lines in Figure 3, will be between the second and third tubes so that the liquid will return to the first mentioned baffle space through the second tube.

Directed from one tube to the other by these alternately disposed vertical baffle partitions 13, the water will travel through all of the tubes of the bottom row. Until it leaves the last tube, it is prevented from passing upwardly into the next row of tubes, by a horizontal partition 14. As shown in Figure 3, this first horizontal partition is turned upwardly at a right angle over the last tube of the bottom row and in front of the last tube of the second row. The water is thus permitted to pass from the last tube of the bottom row to the last tube of the sec-

ond row for passage through each tube of that row, as directed by the alternately disposed vertical baffle partitions 13, until it reaches the front side of the header casting. Here it is permitted to pass upwardly to the first tube in the third row by the second horizontal partition 14 which turns upwardly at a right angle above the first tube in the second row and behind the first tube in the third row.

This zig zag course of the water through each row of tubes before it enters the one above, continues until it is discharged in a thoroughly heated condition, or as steam, into an outlet passage 16. This thorough circulation of the water through the rows of tubes and baffles in contact with the flames of the burner 3, makes it hot or converts it into steam with a minimum waste of heat. When the burner is turned high, steam will be formed in the tubes for passage into the outlet 16.

Communicating with this outlet is a curved passage 17 in the circular base 18 for a storage tank 19. This base is preferably a casting formed with a vertical annular flange 20 that receives the bottom of the tank 19 as a tight fit.

A vertical tube 21 communicates at its lower end with the outlet passage 17 to conduct the hot water or steam to the upper part of the storage tank 19 as shown in Figure 1. From a point just above the bottom of this tank a tube 22 projects downwardly to conduct the cooler water or condensed steam to the inlet 15 in the base 1 for recirculation through the hot tubes and side spaces of the header casting 6.

The hot gases from the burner 3 pass upwardly through holes in the storage tank base into gas passages 23 between the wall of said tank and that of an outer housing or shell 24 which surrounds the entire heater unit as shown in Figure 1.

Opposite each cover plate 11 there is formed in the shell 24 an opening which is closed by a hinged door 25. When it is desired to clean the tubes 8, these doors are opened and the cover plates 11 withdrawn by removing the studs 10. Complete accessibility is thus given to the tubes 8 for the purpose of easily removing all sediment which has accumulated within them. This may be accomplished by the use of a steel brush if desired.

Having described my invention, I claim:

1. An apparatus of the type described, comprising a burner casing, a tier of horizontal rows of tubes above said casing, spaced headers for said tubes, cover plates secured to said headers beyond the ends of the tubes to form water-receiving spaces between said headers and plates, a storage tank mounted on said headers, a water inlet connection between the bottom of the storage tank and one end of the

first tube of the bottom row, a water outlet connection between the last tube of the top row and the upper part of the storage tank, and baffle means disposed in the space between the headers and the cover plates to direct the incoming water, first through all the tubes in one row, and then through all the tubes in the row above, until it has passed through all the tubes into, and through, the water outlet into the top portion of the storage tank.

2. An apparatus of the type described, comprising a burner casting, a tier of horizontal rows of tubes above said burner, spaced headers for said tubes, cover plates secured to said headers beyond the ends of the tubes, to form water-receiving spaces between said headers and plates, a storage tank mounted on said headers, a water inlet connection between the bottom of the storage tank and one end of the first tube of the bottom row, a water outlet connection between the last tube of the top row and the upper part of the storage tank, and horizontal and vertical baffle partitions disposed in the space between the headers and the cover plates to direct the incoming water, first through all the tubes in one row, and then through all the tubes in the row above, until it has passed through all the tubes into, and through, the water outlet into the top portion of the storage tank.

In testimony whereof I have hereunto set my hand this 18th day of May, 1929.

JOSEPH J. GAGE.
